UNITED STATES PATENT OFFICE.

BJARNE CARLÉN, OF NORDSTRAND, NEAR CHRISTIANIA, NORWAY.

SILENCER FOR INTERNAL-COMBUSTION ENGINES.

1,382,472.

Specification of Letters Patent. Patented June 21, 1921.

Application filed June 21, 1919. Serial No. 305,834.

To all whom it may concern:

Be it known that I, Bjarne Carlén, a subject of the King of Norway, residing at Nordstrand, near Christiania, Norway, have 5 invented certain new and useful Improvements in Silencers for Internal-Combustion Engines; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 The present invention relates to silencers for internal combustion engines of the type, in which the exhaust gases are conducted from the motor to the atmosphere through a number of narrow slots serving to minimize 20 the noise of the exhaust. According to the present invention the exhaust gases are conducted through a number of narrow slots arranged in a circular row and being passed by the gases in the direction from their circumference toward the center so that the 25 several branch currents of the exhaust meet in the center of the slots.

Several embodiments of the invention are 30 illustrated on the accompanying drawing. Figure 1 is an axial section through one form of the invention and Fig. 2 is a section on the line 2—2 of Fig. 1. Fig. 3 represents an axial section of another form of the invention and Fig. 4 is a section on the line 35 4—4 of Fig. 3. Fig. 5 is a section similar to Fig. 3, illustrating a slight modification of this form of the invention. Fig. 6 represents another form of the invention and Fig. 7 is a section on the line 7—7 of Fig. 6. Fig. 40 8 is an axial section through a modified construction of the silencer illustrated on Fig. 6, and Fig. 9 is a section on the line 9—9 of Fig. 8. Fig. 10 is an axial section through a modification of the silencer illustrated in 45 Figs. 6 to 9.

In all the embodiments of the invention illustrated the exhaust is introduced into the silencer through a channel 1 and let out through another channel 2, the channel 1 50 conducting the gases to an annular channel 3 which communicates with a central chamber 4 through a number of narrow slots, and the channel 2 leads from the chamber 4 toward the atmosphere.

55 In the forms of the invention illustrated in Figs. 1 to 5 the slots connecting the annu-

lar channel 3 with the central chamber 4 are formed between a number of wedge shaped radial vanes 5.

For convenience of construction the casing 60 of the silencer may consist of two main parts 6 and 7, which are connected by means of flanges 8 and carry each one half of the radial vanes 5 in such a manner that every second vane is cast integral with the member 65 7, while the other vanes are cast integral with the members 6.

The inlet tube 1 may be arranged axially with regard to the channel 3 as illustrated in Figs. 1 and 2 or tangentially as illustrated 70 in Figs. 4 and 9.

For the purpose of facilitating the milling of the side faces of the vanes the adjacent surfaces of the vanes belonging to the same half of the silencer casing are made parallel 75 i. e. the adjacent surfaces of every second vane as seen in Figs. 2 and 4 are parallel.

The forms of the invention illustrated in Figs. 6 to 9 differ from the forms described above, only therein that annular disks 9 80 with wedge shaped cross-section are substituted for the radial vanes 5 in Figs. 1, 2 and 5.

In Figs. 1—9 the vanes 5 are arranged in a circle eccentric to the casing so that the 85 chamber 3 is spiral in form. The spaces between the vanes receive the gases at their narrow ends at the outer periphery of the circle of vanes and discharge the gases after expanding them, at the center of the circle 90 of vanes. The gases in Figs. 1, 2, 6 and 7 are admitted to chamber 3 and simultaneously to the inlets of the spaces between the vanes over the edge of a distributing plate 7^a, 95 i. e., they are supplied around the periphery of the vane sets, while in Figs. 3, 4, 5, 8 and 9 the gases are admitted at the larger end of the chamber 3 tangentially to the vane sets.

In the modification illustrated in Fig. 10 100 the annular disks 9 are not wedge shaped but conical, the conicity of each disk being a little bigger than the conicity of the next one, so that the slots formed between the disks has a wedge shaped cross-section.

Claims:

1. An exhaust silencer, comprising a casing, vanes arranged in a circle in said casing and spaced from the sides of the casing to form a peripheral chamber, said vanes 110 being straight and flared from their inner ends to their outer ends thereby forming

straight tapered expansion passages from the periphery to the center of said series, an inlet for said chamber and an outlet at the center of said series of vanes.

5 2. An exhaust silencer, comprising a casing, vanes arranged in a circle and eccentrically in and spaced from the sides of said casing, said vanes being wider at their periphery than at the center and forming straight tapering expansion passages widening toward the center, an inlet on the casing to said chamber and an outlet on the casing at the center of the circle of vanes.

15 3. An exhaust silencer, comprising a circular two-part casing, a circular series of vanes on one casing part and a similar series on the other casing part, the vanes of one series alternating with the vanes on the other series to form expansion passages en-

20 larging toward the center, the adjacent faces of two vanes of the same series being parallel plane surfaces, an inlet on one part of the casing and an outlet on the other part at the center of said vanes.

25 4. An exhaust silencer comprising two diskshaped members adapted to form one hollow diskshaped body, a circular row of radial vanes inside said hollow body, said radial vanes being alternately cast integral with one and the other, of said diskshaped members, and dividing the interior of said hollow body in an exterior annular channel, a central chamber and a number of radial slots leading from said annular channel to

35 said central chamber.

5. An exhaust silencer comprising two diskshaped members adapted to form one

hollow diskshaped body, a circular row of radial vanes inside said hollow body, said radial vanes being alternately cast integral ⁴⁰ with one and the other of said disk-shaped members, the adjacent side faces of the vanes belonging to one disk member being parallel said row of vanes dividing the interior of said hollow body in an exterior annular channel, a central chamber and a number of radial slots leading from said annular channel to said central chamber.

6. In a muffler, a casing, a series of straight tapered vanes therein spaced from the peripheral walls of said casing to form a gas chamber, said vanes forming between them narrow nozzles at their outer ends that gradually enlarge toward the center, means to direct exhaust gases into said peripheral chamber, and a central discharge.

7. In a muffler, a casing having a chamber at its periphery, an inlet to said casing, a distributor to distribute gases around said chamber from said inlet, an annular series ⁶⁰ of straight tapered vanes forming narrow slot-like nozzles between their outer ends adjacent said chamber, said nozzles gradually enlarging to the narrow ends of said vanes, and a discharge at the center of said ⁶⁵ vanes.

In testimony that I claim the foregoing as my invention, I have signed my name in presence of two subscribing witnesses.

BJARNE CARLEN.
